UNITED STATES PATENT OFFICE.

HERMAN L. KUTTER, OF HAMILTON, OHIO.

PAPER-MAKING MACHINE.

Application filed August 28, 1922. Serial No. 584,710.

To all whom it may concern:

Be it known that I, HERMAN L. KUTTER, a citizen of the United States, and resident of Hamilton, in the county of Butler and State of Ohio, have invented a certain new and useful Improvement in Paper-Making Machines, of which the following is a full, clear, concise, and exact description, reference being had to the accompanying drawing, forming a part of this specification.

The present invention relates to paper making machines, especially of the Fourdrinier type, and its object is to provide for the better composition of the sheet of paper as it is formed on the wire-cloth.

In the drawing which illustrates a typical Fourdrinier machine, with all parts which are unnecessary to an understanding of the present invention omitted,—

Figure 1 is a side elevation of a machine embodying the invention.

Figure 2 is a partial vertical section thereof, and

Figure 3 is a broken plan view of a plate forming part of the invention.

The machine employs the usual breast-roll 1 and the table 2 on which the usual table-rolls 3 are rotatably mounted. The endless wire-cloth 4 passes around the breast-roll 1 and thence forwardly over the table-rolls 3. The table may be of the vibrating type or not as desired.

The water containing the fibres from which the sheet of paper is to be formed flows over the apron-board 5 and the rubber apron 6 and onto the wire-cloth 4 approximately at the breast-roll 1. The sheet of paper is formed to a large extent by the passage of excess water through the wire-cloth between the end of the rubber apron 6 and the first table-roll 3. If the passage of water through the wire-cloth be unimpeded between the rubber apron and the first table-roll, the water passes through the wire-cloth so immediately and in such large volume just forwardly of the apron that the sheet of paper is largely formed at once with its full thickness. Such rapid formation of the sheet tends to produce such a distortion of the fibres as to produce a poorly constituted sheet and this distortion is greatly enhanced if the wire table vibrates as it does in the more common form of Fourdrinier machine.

In accordance with the present invention a transverse plate 7 is suitably supported immediately under the wire-cloth 4 between the

breast-roll 1 and the first table-roll 3. The plate 7 is formed with a plurality of perforations 8. Preferably, but not necessarily, the perforations 8 are formed as elongated slots, and preferably, but not necessarily, the perforations are arranged in spaced series of transverse rows with the perforations in staggered relation, as illustrated in Figure 3. The rubber apron 6 ordinarily projects over the rear edge of the plate 7 so that no water may flow through the wire-cloth 4 until the water and fibres reach the first row of perforations 8 in the plate. It may be desirable, however, in the formation of certain kinds of sheets, to move the rubber apron 6 back far enough to permit a slight and limited amount of water to pass through the wire-cloth before the rear edge of the plate 7 is reached.

In the preferred and usual installation in which the rubber apron projects beyond the rear edge of the plate 7, as the wire-cloth and water and fibres move forwardly no water is permitted to pass through the wire-cloth until the first row of perforations in the plate 7 is reached. When the first row of perforations is reached, a limited quantity of water passes through the wire-cloth and further limited quantities of water pass through the wire-cloth as the successive rows of perforations are reached. As a consequence, the fibres tend to deposit in superimposed layers so that the sheet is made up of a plurality of thin laminations with properly and regularly formed fibres. During the passage of the sheet thus formed over the succeeding table-rolls and through the press-rolls, the laminations are compacted into a homogeneous sheet but with an absence of distortion of the fibres.

Having thus described my invention, what I claim as new and desire to secure by Letters Patent of the United States is:—

1. In a Fourdrinier machine, the combination of a forwardly movable wire-cloth, and a perforated plate underlying the wire-cloth adjacent the rear end thereof.
2. In a Fourdrinier machine, the combination of a forwardly movable wire-cloth, and a plate underlying the wire-cloth adjacent the rear end thereof, the plate being formed with perforations arranged one forwardly of another.

3. In a Fourdrinier machine, the combination of a forwardly movable wire-cloth, and a plate underlying the wire-cloth adj-

cent the rear end thereof, the plate being formed with perforations arranged in transverse rows.

4. In a Fourdrinier machine, the combination of a forwardly movable wire-cloth, and a plate underlying the wire-cloth adjacent the rear end thereof, the plate being formed with transversely elongated perforations arranged in transverse rows.

10 5. In a Fourdrinier machine, the combination of a breast-roll, a series of table-rolls, a wire-cloth movable around the breast-roll and forwardly over the table-rolls, and a perforated plate underlying the wire-cloth

15 between the breast-roll and first table-roll.

6. In a Fourdrinier machine, the combination of a breast-roll, a series of table-rolls, a wire-cloth movable around the breast-roll and forwardly over the table-rolls, and a 20 plate underlying the wire-cloth between the breast-roll and first table-roll, the plate being formed with perforations arranged in transverse rows.

7. In a Fourdrinier machine, the combination of a breast-roll, a series of table-rolls, a wire-cloth movable around the breast-roll and forwardly over the table-rolls, and a 25 plate underlying the wire-cloth between the breast-roll and first table-roll, the plate being formed with transversely elongated perforations arranged in transverse rows.

8. In a Fourdrinier machine, the combination of a breast-roll, a series of table rolls, a wire-cloth movable around the breast-roll 30 and forwardly over the table-rolls, a perforated plate underlying the wire-cloth be-

tween the breast-roll and first table-roll, and an apron preventing passage of water through the wire-cloth in advance of the plate.

40 9. In a Fourdrinier machine, the combination of a breast-roll, a series of table-rolls, a wire-cloth movable around the breast-roll and forwardly over the table-rolls, a plate underlying the wire-cloth between the breast-roll and first table-roll, the plate being formed with perforations arranged in transverse rows, and an apron preventing passage of water through the wire-cloth in advance of the plate.

45 10. In a Fourdrinier machine, the combination of a breast-roll, a series of table-rolls, a wire-cloth movable around the breast-roll and forwardly over the table-rolls, and a plate underlying the wire-cloth 50 between the breast-roll and first table-roll, the plate being formed with perforations arranged one forwardly of another.

55 11. In a Fourdrinier machine, the combination of a breast-roll, a series of table-rolls, a wire-cloth movable around the breast-roll and forwardly over the table-rolls, a plate underlying the wire-cloth between the breast-roll and first table-roll, the plate being formed with perforations arranged one forwardly of another, and an apron preventing passage of water through the wire-cloth in advance of the plate.

60 In witness whereof, I hereunto subscribe my name this 9th day of August, 1922.

HERMAN L. KUTTER.
